UNITED STATES PATENT OFFICE

CURT W. KLOSTERMANN, OF CHICAGO, ILLINOIS

DESIGN FOR A VENDING-MACHINE CASE

Application filed December 23, 1929. Serial No. 33,899. Term of patent 3½ years.

To all whom it may concern:

Be it known that I, CURT W. KLOSTERMANN, a citizen of Germany, residing at Chicago, in the county of Cook and State of Illinois, have invented a new, original, and ornamental Design for a Vending-Machine Case, of which the following is a specification, reference being had to the accompanying drawing, forming a part thereof, which is a perspective view of a vending-machine case showing my new design, the opposite or undisclosed side of the case being substantially like the side shown, and the rear side of the case being a substantially flat surface.

I claim:

The ornamental design for a vending machine case, as shown and described.

CURT W. KLOSTERMANN.
